(57) CLAIM

I claim the ornamental design for a table, as shown and described.

DESCRIPTION

FIG. 1 is a front perspective view of the table according to the claimed design in closed condition;

FIG. 2 is a top plan view of the table as shown in FIG. 1;

FIG. 3 is a bottom plan view of the table of FIG. 1;

FIG. 4 is a front elevational view of the table of FIG. 1;

FIG. 5 is a rear elevational view of the table of FIG. 1;

FIG. 6 is a right side elevational view of the table of FIG. 1;

FIG. 7 is a left side elevational view of the table of FIG. 1;

FIG. 8 is a front perspective view of the table of FIG. 1 shown in its open operational condition; and,

FIG. 9 is a front elevational view of the table in open operational condition according to FIG. 8.
